REFRIGERATING APPARATUS

Lawrence A. Philipp, Detroit, Mich., assignor, by
mesne assignments, to Nash-Kelvinator Cor-
poration, Detroit, Mich., a corporation of Mary-
land

Application March 22, 1933, Serial No. 662,057

8 Claims. (Cl. 62—115)

This invention relates to refrigerating apparatus, and more particularly to refrigerating apparatus of the multiple temperature type.

One of the objects of my invention is to provide an improved refrigerating system for freezing substances and for cooling circulating air in a refrigerator cabinet.

Another object of my invention is to provide a simplified arrangement for attaining a temperature differential between a number of different refrigerant evaporators in a refrigerating system.

Another object of my invention is to provide an improved refrigerating system and controls therefor for maintaining different temperatures within predetermined ranges in different parts of a refrigerator cabinet.

Another object of my invention is to provide within a refrigerator cabinet an improved arrangement of and control for refrigerant evaporating means, which is arranged and operated without the collection of frost thereon or a slight film of frost is allowed to collect thereon during the on-phase of the refrigerating cycle and is melted off during the off-phase of the refrigerating cycle, while at the same time provisions are made for freezing substances, such as ice cubes and the like, and for cooling circulating air in the food storage compartment whereby, continuous refrigeration at substantially constant predetermined temperatures is assured and the necessity of periodic inoperative conditions of the system for defrosting is avoided.

Another object of my invention is the simplicity of parts and their arrangement within the refrigerator cabinet whereby the aforesaid objects may be economically and easily carried out.

Other objects and advantages will be apparent from the following description, reference being had to the accompanying drawing.

In the drawing:

Fig. 1 is a vertical view, partly in cross section and partly in elevation, of a refrigerating apparatus embodying features of my invention;

Fig. 2 is a fragmentary view of the apparatus shown in Fig. 1, taken in the direction of arrows 2—2 in Fig. 1;

Fig. 3 is a vertical view in cross section of a control valve embodying features of my invention; and

Fig. 4 is a view taken along the line 4—4 of Fig. 3.

Referring to the drawing, the numeral 20 designates, in general, a cabinet having a compartment 22 for the storage of foods to be re-

frigerated, a freezing compartment 23, and a machine compartment 24. The cabinet is constructed of insulating walls, including side walls 26, rear wall 21, front wall 28, bottom wall 29 and top wall 30. The cabinet also includes a 5 fixed, vertical insulating wall 32 which extends from the rear wall 21 to the front wall 28 and from the top wall 30 to the bottom wall 29, separating the food compartment from the freezing compartment. An inner metallic lining member 10 35 forms the inner walls of the food compartment and is, preferably, provided with a coating of vitreous enamel, such as porcelain, to provide a neat appearing compartment and one which may be easily cleaned. A similar inner metallic lining member 37 forms the inner walls of the compartment 23. The liner 37 may be coated the same as liner 35. The front wall 28 is provided with an opening 38 through which access may be had to the food compartment 22. The opening 38 is closed by door 40. A second opening may be provided in the front wall 28 in advance of the freezing compartment 23 for gaining access to the compartment 23. Any suitable door (not shown) may be used for closing the latter opening in wall 28.

Within the freezing compartment 23 is disposed a refrigerant evaporator 45 which is suspended from wall 30 by brackets 47. The evaporator 45 comprises, in general, a header 49 which has 30 a space within its interior for both liquid and gaseous refrigerants. Depending upon the header 49 are a plurality of conduits 50. To the conduits 50 are attached a plurality of vertically spaced refrigerant containing shelves 51. The 35 shelves 51 are provided for supporting ice making receptacles (not shown). Liquid refrigerant is delivered to the shelves 51 through conduits 50, which are in open communication on their upper ends with the header 49 and also in open 40 communication with the interior of each of the shelves 51. Preferably, the shelves are constructed of sheet metal plates suitably secured together by welding but spaced apart between the sheets of metal. By operating the evaporator 45 at sufficiently low enough temperatures and by supporting the ice making receptacles on the upper surfaces of the refrigerant containing plates, the water in the receptacles will be rapidly frozen. If desired, desserts and the like may be 45 placed in the receptacles stored on the shelves 51. Also, if desired, the frozen desserts and the like may be removed when frozen from the shelves and placed on the top of the wall 28 in compartment 23 immediately below the evaporator 45 55

where the substances will be retained in a frozen condition.

Within the food compartment 22 there is disposed a refrigerant evaporator 55. Evaporator 55 is of the plate type and is secured to the wall 32. As will be noted in the drawing, the evaporator 55 extends over the major portion of wall 32 within compartment 22. By providing an evaporator of this size and by so locating it in compartment 22, it is possible to substitute for the insulated wall 32 a thin metallic wall since the evaporator is arranged to prevent the transfer of heat from the compartment 22 into the compartment 23. Preferably, the evaporator 55 is constructed of sheet metal plates which are secured together about their peripheries thereof by seam welding and welded at various points intermediate their edges but spaced apart between the welded points to provide a space for refrigerant. In order to increase the heat transfer characteristics of evaporator 55, I have provided a plurality of spaced parallel fins 57 on one side of the evaporator 55.

A refrigerant condensing element 60 is disposed in the machine compartment 24. This element may be supported in compartment 24 by any suitable means (not shown). The element includes a compressor 62, motor 63 for operating the compressor, condenser 65 and high side float mechanism 67. The compressor 62 withdraws evaporated refrigerant from the evaporators 45 and 55 through a vapor conduit 69, compresses the evaporated refrigerant and delivers it to the condenser wherein it is liquefied and from which it is delivered to the high side float mechanism 67. Liquid refrigerant is delivered to the evaporators through liquid supply conduit 70 under the control of float mechanism 67.

Liquid refrigerant is first delivered to evaporator 55 through a conduit 70, and from the evaporator 55 liquid and gaseous refrigerant is delivered to the evaporator 45 through conduit 72. Evaporated refrigerant is withdrawn from the evaporator 45 through the vapor conduit 69.

Preferably, the condensing element is intermittently operated. In order to control the operation of condensing element, I have provided thermostatically controlled switches 75 and 77. To the switches 75 and 77 are connected thermostatic fluid containing bulbs 79 and 82 by means of conduits 83 and 84, respectively. Bulbs 79 and 82 are disposed in thermal contact with the evaporators 45 and 55, respectively, so that the switch 75 operates in response to changes in temperatures in evaporator 45, and switch 77 operates in response to changes in temperatures in evaporator 55. Switches of this type are well known in the art and further illustration thereof in the drawing is deemed unnecessary. Thus, it will be noted that the operation of motor 63 is controlled in response to changes in temperatures in either or both of the evaporators. In view of the fact that the evaporators 45 and 55 are of the so-called flooded type, the temperatures therein 65 bear direct relation to the pressure existing therein.

In order to maintain a predetermined temperature differential between the evaporators 45 and 55 during operation of the condensing element, I have provided a pressure responsive valve 105 which is interposed in the conduit 72 for controlling the flow of liquid and gaseous refrigerant from the evaporator 55 to the evaporator 45. The pressure responsive valve 105 is adapted to

maintain a predetermined pressure differential between the evaporators 55 and 45 during operation of the condensing element to thus maintain a temperature differential between said evaporators. As shown in Fig. 3, the pressure responsive valve includes a valve proper 107 and valve seat 108 located within a casing 109. The casing 109 is provided with an inlet 110 to which that portion of conduit 72 which extends between the valve 105 and the outlet end of evaporator 55 is connected. The valve 105 is also provided with an outlet 112 to which the evaporator 45 is connected by another portion of the conduit 72. The valve proper 107 is secured to weight 115 which is adapted to move upwardly and downwardly within a chamber 116, depending upon the pressure of the refrigerant exerted on valve proper 107. Preferably, the chamber 116 is cylindrical in shape and also, preferably, the weight 115 is provided with a plurality of arcuate portions 118 which conform to the contour of the walls of the chamber. The weight is also provided with cut-away flat portions 119 between the arcuate portions 118 to provide spaces between the walls of the chamber and the weight so as to prevent binding of the weight in the chamber, and also to prevent a dash pot action therein. When the pressure of the refrigerant in the evaporator 55 reaches a predetermined point, for example, equal to the pressure within the evaporator 45, and is of sufficient force to lift weight 115 and the valve proper, the liquid and gaseous refrigerant will move the valve 107 and weight 115 upwardly to allow liquid and gaseous refrigerant to enter the chamber 116, whence it passes through outlet 112 in conduit 72 into evaporator 45. When the pressure recedes to a predetermined point, for example, to a point less than it requires to open valve 107, the weight and valve proper move downwardly to cause the valve 107 to engage itself with seat 108 to prevent further passage of refrigerant into the evaporator 45. The weighted valve is arranged to be intermittently operated so as to maintain a predetermined pressure differential between the evaporators 45 and 55. As previously stated herein, the pressure differential is controlled by the weight of the weighted valve proper 107. In other words, before refrigerant may pass from the evaporator 55 to the evaporator 45, the pressure within the evaporator 55 must be equal to the pressure in the evaporator 45, plus the amount equal to move the weight 115 upwardly to remove the valve 107 from its seat 108. This predetermined pressure differential is maintained during operation of the condensing element irrespective of the temperature ranges maintained in evaporators 45 and 55.

Preferably, the thermostatic switch 77 is set so that the evaporator 55 will be operated at temperatures which are slightly above that which would be likely to cause the collection of frost or ice thereon due to the deposit of moisture from the circulating air in the food compartment. If desired, the thermostat may be set to operate evaporator 55 at a temperature which would allow a slight film of frost to collect thereon during the on-phase of the refrigerating cycle and melted off during the off-phase of the refrigerating cycle. Preferably, the thermostatic switch 75 is set so as to cause operation of the condensing element at predetermined pressure limits within the evaporator 45 so that said evaporator will be operated at temperatures which cause rapid freezing therein.

In the refrigerating system herein described, I

prefer to use sulphur dioxide as a refrigerant. When sulphur dioxide is used as the refrigerant and when a predetermined setting of the switch 71 is made, I have found that the cyclic operation of the system is between an upper and lower pressure range limit in the evaporator, which limits may be fourteen pounds pressure when the motor cuts in and four pounds pressure of the refrigerant when the motor cuts out. By the use 5 of the pressure responsive valve 105 and by determining the weight member 115 thereof so that a seven pound pressure differential is maintained between the two evaporators during the operating of the condensing element, I have found that 10 when the aforementioned pressure range limits exist in the evaporator 55 that the upper and lower pressure range limits existing in the evaporator 45 extend between an upper limit of 15 four pounds pressure of the refrigerant and lower 20 limit of six inches of vacuum. With such pressure range limits existing in the evaporator 45, it will be noted that the substances may be frozen rapidly.

Assuming that a large quantity of substances to 25 be frozen should be applied to the ice freezing evaporator 45, the pressure of the refrigerant in said evaporator is increased by the heat of the substances. Inasmuch as the thermostatic switch 71 is responsive to changes in temperatures in 30 the evaporator 55, it is necessary to provide some means for immediately initiating operating of the condensing element 60 when a large quantity of substances to be frozen is applied to the evaporator 45 so that the heat absorbed by the 35 refrigerant in the evaporator 45 may be immediately withdrawn to start the process of freezing the said substances. For this reason, the thermostatic switch 75 has been provided. Preferably, the switch 75 is arranged so that it cuts in 40 the motor 63 when the pressure of the refrigerant in the evaporator 45 reaches an upper limit of slightly above four pounds pressure and cuts out the motor 63 when the pressure of the refrigerant falls to six inches of vacuum. Thus, it will be 45 noted that when the pressure in the evaporator 45 exceeds four pounds, the condensing element begins operation to reduce the pressure within the evaporator 45. Preferably, the switches 75 and 71 are connected in parallel so that the 50 switch 71 will control the operation of the condensing element to maintain the desired temperatures within the food storage compartment. Owing to the pressure responsive valve 105, a 55 pressure differential will be maintained between the evaporators 55 and 45 to thus permit the evaporator 45 to operate at low temperatures so that ice cubes may be readily frozen. Thus, it will readily be apparent that provisions are made for both rapid freezing of ice cubes and maintaining the temperatures within the food storage compartment 22 within predetermined range limits, by simply controlling the operation of the condensing element by means of a thermostatic switch 71. However, in order to control the 60 operation of the condensing element so that ice may readily be frozen in the compartment 23, I have provided the thermostatic switch 75 which immediately cuts the motor-compressor unit into operation when the pressures within the evaporator 45 rise to slightly above four pounds irrespective of the pressures existing in evaporator 55. Thus, it will be noted that the pressure responsive switch 75 is included for promoting rapid ice freezing.

75 Although I have described my pressure dif-

ferential valve 105 in connection with an intermittently operated refrigerating system, it will readily be apparent from the foregoing that said valve may be used advantageously in a continuously operated system where it would maintain a predetermined pressure differential between the evaporators 45 and 55 at all times.

From the foregoing, it will be noted that I have provided an improved and simple arrangement for maintaining a pressure differential between a number of different evaporators and for maintaining a temperature differential therebetween. It will also be noted that the pressure differential is obtained automatically as the pressures in the evaporators are being reduced by the condensing element. In addition, it will be noted that said predetermined pressure differential is maintained irrespective of the setting of the thermostatically controlled means for controlling the operation of the condensing element.

In order to prevent refrigeration taking place immediately upon entrance of the liquid refrigerant into the supply conduit 70 after leaving the high side float mechanism 61, I have provided a pressure responsive valve, designated by the numeral 120. This valve is interposed in the conduit 70 adjacent the inlet of the evaporator 55. This valve maintains the pressures in the supply conduit 70 sufficiently high enough so as to prevent refrigeration taking place in said conduit so that no refrigeration takes place before entering the evaporator 55. This prevents loss of refrigeration, increases the capacity of the apparatus and prevents the collection of moisture in the insulated portions of the food storage compartment through which the liquid supply conduit 70 extends. Preferably, the valve 120 is of the same construction as the valve 105, with the weighted member 115 being of different size so as to maintain the pressure of refrigerant within the conduit 70 above that which would cause the collection of frost on the conduit 70. Thus, it will be noted that within the refrigerating system described herein, there are four portions thereof in which the pressures are different. For instance, a relatively high pressure within the condenser 65, the pressure in the conduit 70 which is somewhat below the pressure existing in the condenser and above the pressure existing in the evaporator 55, and a relatively low pressure which exists in the evaporator 45.

Although only a preferred form of the invention has been illustrated, and that form described in detail, it will be apparent to those skilled in the art that various modifications may be made therein without departing from the spirit of the invention or from the scope of the appended claims.

What I claim as my invention is:

1. A refrigerating system comprising a refrigerant condensing element, a number of different refrigerant evaporators connected in series, means connected in said system for maintaining a predetermined temperature differential between the different evaporators during the operation of said condensing element, and means associated with each evaporator for controlling the operation of said condensing element.

2. A refrigerating system comprising a refrigerant condensing element, a low temperature refrigerant evaporator, a relatively high temperature refrigerant evaporator, control means responsive to changes in conditions within said relatively high temperature evaporator for initiat-

60

65

70

75

ing operation of said condensing element when the temperature of the refrigerant in said relatively high temperature evaporator attains a certain high value, and for interrupting the operation of said element when said temperature is reduced to a certain low value, auxiliary control means for controlling operation of said condensing element only in the event the temperature in said low temperature evaporator exceeds the aforesaid certain low value and means for maintaining a predetermined pressure differential between said low and high temperature evaporators during operation of said condensing element.

3. A refrigerating system comprising a refrigerant condensing element, a number of different refrigerant evaporators, means for obtaining a substantially constant temperature differential between said evaporators, and independent temperature responsive means for controlling the operation of said condensing element, one of said temperature responsive means being operable to normally control the operation of the condensing element to maintain said temperature differential, and the other temperature responsive means being operable only in the event of a predetermined demand for refrigeration by one of said evaporators to control the operation of said condensing element to thereby insure maintaining said substantially constant temperature differential at all times.

4. A refrigerating system comprising a number of different refrigerant evaporating elements, means for simultaneously reducing the pressures in said elements, temperature differential means for maintaining a predetermined temperature differential between said elements, control means normally controlling the operation of the means for reducing said pressures, and auxiliary control means arranged to be effective to control the operation of said pressure reducing means in the event the temperatures in one of said evaporators is increased to a certain amount.

5. A refrigerating system comprising a low temperature evaporator, a relatively high temperature evaporator, pressure reducing means

associated with said evaporators, means for maintaining a predetermined pressure differential between said evaporators during operation of said pressure reducing means, and means directly associated with said low temperature evaporator for controlling the operation of said pressure reducing means.

6. A refrigerating system comprising a low temperature evaporator, a relatively high temperature evaporator, pressure reducing means associated with said evaporators, means for maintaining a predetermined pressure differential between said evaporators during operation of said pressure reducing means to maintain a predetermined temperature differential between said evaporators, and independent means directly associated with each evaporator for controlling the operation of said pressure reducing means.

7. A refrigerating system comprising a refrigerant condensing element, a refrigerant evaporator, a second refrigerant evaporator connected in series with the first named evaporator, a pressure responsive valve connected in said system for controlling the flow of liquid and gaseous refrigerant from the first evaporator to the second to maintain a predetermined temperature differential between said evaporators during the operation of said condensing element, and means associated with each of said evaporators for controlling the operation of said condensing element.

8. A refrigerating system comprising a refrigerant condensing element, a refrigerant evaporator, a second refrigerant evaporator connected in series with the first named evaporator, a pressure responsive valve connected in said system for controlling the flow of liquid and gaseous refrigerant from the first evaporator to the second to maintain a predetermined temperature differential between said evaporators during the operation of said condensing element, and thermostatic means directly associated with each of said evaporators for controlling the operation of said condensing element.

LAWRENCE A. PHILIPP. 45
